CLAIM

The ornamental design for a face mask, as shown and described.

DESCRIPTION

FIG. 1 is a front, side and top perspective view of a face mask showing my new design;

FIG. 2 is a back, side, and bottom perspective view thereof;

FIG. 3 is a front view thereof;

FIG. 4 is a back view thereof;

FIG. 5 is a first side view thereof;

FIG. 6 is a second side view thereof;

FIG. 7 is a top view thereof;

FIG. 8 is a bottom view thereof;

FIG. 9 is an exploded top view thereof; and,

FIG. 10 is an exploded, back, side and bottom perspective view thereof.

1 Claim, 10 Drawing Sheets
